UNITED STATES PATENT OFFICE.

HERBERT A. STREETER, OF CHICAGO, ILLINOIS.

METAL CLIP FOR USE IN STEEL BUILDING CONSTRUCTIONS.

SPECIFICATION forming part of Letters Patent No. 718,545, dated January 13, 1903.

Original application filed March 17, 1900, Serial No. 9,021. Divided and this application filed July 30, 1900. Serial No. 25,225. (No model.)

To all whom it may concern:

Be it known that I, HERBERT A. STREETER, a citizen of the United States, residing in Chicago, in the county of Cook and State of Illinois, have invented a new and useful Improvement in Metal Clips for Uniting, Spacing, and Supporting Beams and Bars in Steel Building Constructions, of which the following is a specification.

10 My invention relates to metal clips used in the construction of steel-frame work buildings or structures in which the roofs, floors, or ceilings are formed or supported by steel beams or bars crossing each other.

15 My present application is a division of my pending application, Serial No. 9,021, filed March 17, 1900, on clips for steel building constructions.

20 My invention consists in the novel construction of parts and devices, and in the novel combinations of parts and devices herein shown and described, and specified in the claims.

25 In the accompanying drawings, forming a part of this specification, and in which similar letters of reference indicate like parts throughout, Figure 1 is a perspective view of a device embodying my invention, and Fig. 2 is a detail perspective view of my improved clip.

30 In the drawings, A A' and B B' represent crossing steel beams or bars of a building or other structure, the beams or bars being of any suitable or customary form in cross-section—such, for example, as I-beams, T-beams, 35 angle-beams, channel-beams, or other desired shape.

D is a metal strap-clip, made of strap or band metal—that is to say, iron or steel rolled into narrow strips. The clip D is specially 40 designed for use at the meeting ends of two beams or bars B B' or A A', one or both.

The clip D has folds d d at each end embracing the edges or flanges of the beams A A', and thus serving to join or unite the same together at their meeting ends. The clip D is further provided with flanges d' d', extended at an angle—as, for example, a right angle—to the plane of the clip, and each of the flanges d' is furnished with an eye or opening d² to 45 receive and support the crossing beam or bar B or B', the two flanges d' d' of the clip D thus serving to unite the meeting or abutting

ends of the two crossing beams or bars B and B'.

In my improved clip it will be seen that the 55 bends, folds, or flanges d d d' d' are each and all formed across the length of the strip—that is to say, across the fiber of the metal—and for this reason my improved clip possesses great strength for the weight of metal employed 60 therein and is not liable to give way or fail, as is the case where clips are provided with bends or folds parallel to the fiber or grain of the metal or to the direction in which the metal is rolled. The flanges d' d' are sufficiently far apart to enable the meeting or abutting ends of the two beams or bars B B' to extend each well through one of said flanges and have proper support thereon, and the width of the clip D is such as to enable the 70 clip and its folds d d to properly embrace and give suitable bearing for the two meeting or abutting ends of two beams or bars A A' when it is desired to join or unite the same.

In the drawings I have illustrated the beams 75 B B' as extending at right angles to the beams A A', as this is the more usual construction; but the beams B B' may extend at any other angle, it being of course understood that the flanges d' d' on the clip should in every case 80 be turned so as to extend about at right angles to the direction of the beams that pass through said flanges.

I claim—

1. The combination with two beams abutting at their ends, and a transverse bar or bars, of a single metal strap-clip, having folds embracing the flanges of both said beams, and also having vertical flanges with perforations for said transverse bar or bars, substantially 90 as specified.

2. In a steel building or other structure, the combination with two abutting beams or bars A A' and transverse bars B B', of a metal clip D having folds d d embracing and connecting 95 the meeting ends of said bars A A', and provided with flanges d' d', having eyes d² through the same to receive the meeting ends of said two bars B B', substantially as specified.

HERBERT A. STREETER.
